DESIGN FOR A SHIRT COLLAR CLIP

Edward H. Fowler, Pacific Palisades, Calif.

Application November 3, 1941, Serial No. 104,004

Term of patent 14 years

To all whom it may concern:

Be it known that I, Edward H. Fowler, a citizen of the United States and resident of Pacific Palisades, Los Angeles County, State of California, have invented a new, original, and ornamental Design for a Shirt Collar Clip, of which the following is a specification, reference being had to the accompanying drawing, forming a part thereof.

I claim:

The ornamental design for a shirt collar clip, substantially as shown.

EDWARD H. FOWLER.
